US00D779694S

(12) **United States Design Patent** (10) **Patent No.:** **US D779,694 S**
(45) **Date of Patent:** **** Feb. 21, 2017**

(54) **PORTABLE LIGHT**

(71) Applicant: **Milwaukee Electric Tool Corporation**,
Brookfield, WI (US)

(72) Inventors: **Jason R. Crowe**, Milwaukee, WI (US);
Justin D. Dorman, Wauwatosa, WI
(US); **Timothy Janda**, Kenosha, WI
(US)

(73) Assignee: **MILWAUKEE ELECTRIC TOOL
CORPORATION**, Brookfield, WI (US)

(**) Term: **14 Years**

(21) Appl. No.: **29/465,484**

(22) Filed: **Aug. 28, 2013**

Related U.S. Application Data

(63) Continuation-in-part of application No. 14/011,032,
filed on Aug. 27, 2013, now Pat. No. 9,157,585.

(57) **CLAIM**

We claim the ornamental design for a portable light, as
shown and described.

DESCRIPTION

FIG. 1 is a perspective view of a portable light embodying
the invention;

FIG. 2 is a bottom view of the portable light of FIG. 1;

FIG. 3 is a top view of the portable light of FIG. 1;

FIG. 4 is a right side view of the portable light of FIG. 1;

FIG. 5 is a left side view of the portable light of FIG. 1;

FIG. 6 is a front view of the portable light of FIG. 1; and,

FIG. 7 is a rear view of the portable light of FIG. 1.

The broken line showing represents unclaimed portions of
the article and forms no part of the claimed design.

1 Claim, 7 Drawing Sheets
